(57) **CLAIM**

The ornamental design for a planting device, as shown and described.

DESCRIPTION

FIG. 1 is an environmental perspective view of the planting device in use. The user, the land, and the plants are shown in broken lines to illustrate environment and form no part of the claimed design.

FIG. 2 is a front perspective view of a planting device of my invention;

FIG. 3 is a front view of a planting device of my invention based on FIG. 1;

FIG. 4 is a back view of a planting device of my invention based on FIG. 1 and a reverse view of FIG. 3;

FIG. 5 is a left view of a planting device of my invention based on FIG. 1;

FIG. 6 is a right view of a planting device of my invention based on FIG. 1 and a reverse view of FIG. 5;

FIG. 7 is a top view of a planting device of my invention based on FIG. 1; and,

FIG. 8 is a bottom view of a planting device of my invention based on FIG. 1 and a reverse view of FIG. 7.
